UNITED STATES PATENT OFFICE.

HANS P. HOLT, OF GRAND JUNCTION, COLORADO.

ORCHARD-HEATER.

No. 926,120.

Specification of Letters Patent. Patented June 29, 1909.

Application filed September 23, 1908. Serial No. 454,995.

To all whom it may concern:

Be it known that I, HANS P. HOLT, a citizen of the United States, residing at Grand Junction, in the county of Mesa and State of Colorado, have invented certain new and useful Improvements in Orchard-Heaters, of which the following is a specification.

My invention relates to orchard heaters or smudge pots used to prevent the destruction of the buds on fruit trees by late frosts and also the destruction of tropical vegetation by unclimatic changes of temperature and has for its object the provision of a device simple in construction and made of separable sections so that it is easily and quickly assembled for use, or dismembered for transportation and storage.

My invention will be described in detail hereinafter and illustrated in the accompanying drawings in which—

Figure 1, is a view in elevation of my improved orchard heater, Fig. 2, a central, vertical sectional view, Fig. 3, a top plan view, and Fig. 4, a plan view of the grate section.

In the drawings similar reference characters indicate corresponding parts in the several views.

My improved orchard heater is constructed in three separable sections, viz: the grate section 1, intermediate section 2, and top section 3. The grate section 1 is composed of a ring 4 slightly larger in diameter at its top than at its bottom and provided with three or more supporting legs 5 to space it from the ground so as to permit the passage of air through the ring 4.

6 indicates rods secured across ring 4 and having their ends outside of the ring bent, as shown at 6^a, to hold the rods in place, said rods constituting the grate bars to support the fuel burned in the heater.

The middle section 2 consists of a cylindrical portion 7 smaller in diameter at its bottom than at its top so as to fit the upper

portion of ring 4 and rest therein when the device is assembled.

8 indicates an inwardly flaring flange on the upper edge of cylindrical portion 7 on which is seated the top section 3 that is cone-shaped, as shown, and snugly engages flange 8.

Top section 3 is provided with an opening 9 and a lid 10 is provided for closing the opening having a curved slot 11 therein in which 55 is slidably mounted a securing member 12 secured to section 3.

13 indicates a cup or other receptacle under the heater that may be used for containing a liquid fuel when it is desired to 60 start a quick fire in the heater.

It will be understood from the above description and an inspection of the drawings that the three sections 1, 2 and 3 may be quickly assembled when it is desired to put 65 the device in use, and when not in use that the parts may be as quickly dismembered for transportation and economical storage.

Having thus described my invention what I claim is—

An orchard heater comprising a base ring larger in diameter at the top than at its bottom and having supporting legs secured thereto, a grate secured to said ring consisting of bars diametrically secured to said 75 ring, a middle section smaller in diameter at its bottom than at its top and seated in the upper portion of said base ring and having an inwardly extending flange on its upper edge, a conical top section seated on and supported 80 by the flange aforesaid, a lid for the top section having a curved slot therein, and a securing member secured to said top section and engaging said slot.

In testimony whereof I hereto affix my 85 signature in the presence of two witnesses.

HANS P. HOLT.
